UNITED STATES PATENT OFFICE.

FRANCIS H. RICHARDS, OF HARTFORD, CONNECTICUT, ASSIGNOR TO THE PRATT & WHITNEY COMPANY, OF SAME PLACE.

GRAIN-WEIGHER.

SPECIFICATION forming part of Letters Patent No. 443,583, dated December 30, 1890.

Application filed August 16, 1890. Serial No. 362,214. (No model.)

To all whom it may concern:

Be it known that I, FRANCIS H. RICHARDS, a citizen of the United States, residing at Hartford, in the county of Hartford and State 5 of Connecticut, have invented certain new and useful Improvements in Grain-Weighers, of which the following is a specification.

This invention relates to regulator grain-weighers of the class described and claimed 10 in my application, Serial No. 340,814, filed February 17, 1890, wherein one or more cut-off valves are normally actuated by or from the scale-beam, and are exceptionally actuated by or from a regulator, whereby the cut- 15 off valve is also utilized as a regulator-valve.

The object of my present improvements is to provide in a regulator grain-weigher a regulator apparatus not connected through or with the scale-beam, but operated interme- 20 diate to the valve and its actuator, whereby the regulation is effected by shifting the valve and its actuator relatively to each other by means of a regulator suitably connected therefor.

25 In the drawings accompanying and forming a part of this specification, Figure 1 is an elevation of the left-hand side of the grain-weigher mechanism embodying my present improvements. Fig. 2 is an elevation of the 30 right-hand side of the machine. Fig. 3 is a plan view of the upper part of the machine comprising the valve mechanism. Fig. 4 is a front elevation of the part of the machine shown in Fig. 3 and situated above the grain- 35 bucket. Figs. 5 and 6 are views similar to the upper part of Figs. 1 and 2, respectively, and illustrate the operation of the regulator apparatus. Fig. 7 illustrates one modification of the actuator-shifting means.

40 Similar characters designate like parts in all the figures.

The frame-work for carrying the operative parts of the machine usually, and as shown in the drawings, comprises two side frames 45 or uprights 2 and 4, suitably connected together, the top plate 5 carrying the supply-chute H and supporting the scale-beam and valve mechanism, said top plate being fixed on the top of the uprights by screws, as indicated in the drawings. It will be understood, however, that any suitable form of

frame-work adapted to carry the operative parts of the machine, may be used instead of the particular form herein shown. The position of the grain-bucket G (usually and preferably of the well-known double-chambered oscillating type or class) is indicated by dotted lines in Figs. 1 and 2, where it is shown as if suspended by its pivots 12 underneath the spout 65 of the supply-chute H and over 55 the regulator P. The usual and necessary means for supporting and operating said bucket are not shown in this application, but are set forth in prior Letters Patent, one of said devices suitable therefor being shown in 60 Letters Patent No. 403,988, granted to C. H. Cooley, May 28, 1889.

The regulator P is or may be the same regulator which is described and claimed in the joint Letters Patent to C. H. Cooley and F. H. Richards, No. 434,702, dated August 19, 1890, to which reference may be had for a more particular description thereof. Said regulator consists of a hopper, designated in a general way by the character P, and which 75 is pivotally supported in the frame-work by pivots 98 99. The regulator-hopper is normally upheld, as indicated by dotted lines in Fig. 1, by means of a suitable counter-weight, as 11, fixed on the arm 10, extending 80 from said hopper. Suitable stops (not shown) are usually provided for limiting the working-stroke of the regulator P. For operating the shiftable actuator of the valve mechanism suitable connecting-rods, as 13 and 13^a, 85 are connected to the regulator at 110 and extend upward to connect with the proper parts of the valve mechanism.

The scale-beam B has V-shaped bearings 20 and 22, one at each end thereof, which rest on 90 the pivots or knife-edges 24 and 26, that are suitably supported, as by bearings 23 and 25 on the frame-work. Said scale-beam has the principal arms 19 and 21 furnished with the knife-edges 15 and 17 for supporting the 95 usual hangers (not shown) for carrying the grain-bucket G. Opposite to the arms 19 and 21 the scale-beam has an arm 28, which extends rearwardly and is provided with the knife-edge 27, on which a suitable main 100 weight, as W, is suspended by a suitable hook, as 29.

The reducing-valve 60 is carried by the arms 62 64, which are supported by pivots 61 63, that are fixed in the walls of the supply-chute II. The reducing-valve is furnished 5 with the valve-actuating lever 69, which has a normally-fixed relation to said valve, and is normally operated by the arm 71, that is fixed to the scale-beam arm 21, and actuates the valve on the movement of the scale-beam 10 after the manner described and claimed in the application of C. H. Cooley, Serial No. 338,818, filed January 31, 1890, to which I have permission to refer. The lever 69 is usually weighted, either by a weight formed 15 thereon, as herein shown, or by a weight attached thereto. According to my present improvements, the arm 69 is pivotally supported independently of the valve 60, but in radial alignment therewith, which is conveniently 20 done by placing said arm on the extended pivot 63, as indicated in the drawings.

Extending oppositely to the arm 69 said arm has another arm 321, which is connected at 322 by toggle-links 323 and 324 to the pivot 25 325, fixed in the reducing-valve arm 64, the middle pivot of said toggle-links 323 and 324 being connected by the rod 13^a to the pivot 110 of the regulator-hopper P. When the grain-weigher mechanism is operated normally 30 and the regulator-hopper stands in its uppermost position, (shown by dotted lines in Fig. 1,) said toggle-links stand in a direct line with each other, as in Fig. 5, thereby holding the arm 69 in a normally-fixed position relatively 35 to the reducing-valve. If now while said links are so held the scale-beam arm 71 be lowered from its position in Fig. 5, the reducing-valve will close, as described in the aforesaid application of C. H. Cooley, Serial 40 No. 338,818; and if while standing in said position shown in Fig. 5 the regulator-hopper P is lowered, as indicated by solid lines in Fig. 2, said toggle-links 323 and 324 are thrown out of line, as shown in Fig. 2, thereby shifting 45 the arm or actuator 69 relatively to the valve 60 and closing said valve. On the reverse movement of the regulator the rod 13^a, acting through said toggle-links, replaces the valve and actuator in their aforesaid normal 50 positions when said parts are ready for operating normally by the movement of the scale-beam.

The cut-off valve 70 and its accessory devices are substantially of the kind described 55 and claimed in the joint application of C. H. Cooley and F. H. Richards, Serial No. 358,658, filed July 14, 1890, to which reference may be had for a more particular description thereof. The cut-off valve 70 is carried by the arms 72 60 and 74, which are pivoted at 73 to the supply-chute II. According to my present improvements, the cam-arm of said valve is made separate therefrom, but is shiftably connected thereto. The arm 91 is pivotally supported 65 on the extended pivot 73 and carries the usual cam 68 and some suitable weight, as 90, for the purposes respectively described in said

prior application Serial No. 358,658. Said cam-arm 91 has a projecting arm 326 whose pivot 327 is connected by toggle-links 328 and 329 with the pivot 330, fixed in the valve-arm 72 of the valve 70. The middle connecting-pivot of said toggle-links is also connected by the rod 13 (similar to the rod 13^a) to the pivot 110' of the regulator P for the purpose 75 of shifting said cam-arm relatively to its valve for effecting the automatic regulation of the grain-weigher. When the regulator stands in its uppermost position, (shown by dotted lines in Fig. 1,) the toggle-links 328 and 329 stand in the position shown in Fig. 6, thereby holding the cam-arm, with its cam 68, in a normally-fixed relation to the valve 70, whereby said valve and cam-arm normally operate as a single element of the machine. For operating the valve 70 from the scale-beam the arm 19 of said beam is furnished with an actuator 55, consisting in a small roller carried by a pivot fixed in said arm, as indicated in Figs. 1, 3, and 4. On 90 the vertical movement of the scale-beam said actuator 55 acts upon the arm of the cam 68 to operate the valve after the manner described in said prior application Serial No. 358,658. If now the regulator P is lowered 95 to its position shown in solid lines in Figs. 1 and 2, said toggle-links 328 and 329 will be shifted from their position in Fig. 6 to their position in Fig. 1, thereby shifting the cam-arm 91 relatively to the valve 70 and closing 100 said valve, as shown in Fig. 1.

Each of the valves 60 and 70 being furnished with actuator-shifting devices, substantially as described, each connected with the regulator, both valves are simultaneously closed 105 on the downward movement of the regulator, regardless of the vertical movement of the scale-beam; but it will be understood that the reducing-valve is not necessarily furnished with a shiftable actuator or with actuator-shifting devices, since the grain-weigher will be operative when the valve 70 only is so furnished. In such case, however, the grain-weigher when brought to rest by the action 110 of the regulator will have its grain-bucket 115 partly filled with grain. When it is desired that the grain-weigher, on being stopped by the regulator, shall stop with the grain-bucket empty, it is necessary that each of the valves shall be furnished with the shiftable 120 actuator.

It will be understood that in speaking of the valve and its actuator it is immaterial in respect of the valve 60 whether the arm 69 or the arm 71 be considered as the actuator, 125 but I have adopted the method of so designating that one of the two coacting arms which is shiftable from the operative into an inoperative position. According to my present improvements, the arm 69 is thus arranged, and hence is designated as stated. In respect of the valve 70 and for the same reasons the cam-arm 91 is referred to as the "shiftable actuator," while the roller 55 is 130

considered as the "valve-operating" element of the combination.

The non-essentiality of the described toggle-links as a means for shifting the valve-actuator is illustrated by Fig. 7, wherein a swinging cam is shown substituted for said links. This cam 335 has a cam-groove 340, which engages the pin 325' (corresponding to the stud 325 in Fig. 5) in the arm 64 of the valve 60. The cam is carried by an arm 336, which is pivoted to the stud 322, and is connected at 337 to the regulator-rod 13^a similarly as the said links are connected in the preceding figures. The mode of operation of this actuator-shifting cam is evident from the drawings, and will be fully understood without further explanation.

Having thus described my invention, I claim—

- 20 1. In a grain-weigher, the combination, with the supply-chute, the scale-beam, and a valve for said chute, of a valve-operating arm carried by the beam, a valve-actuator operated by said arm, actuator-shifting means connecting the actuator with the valve, and a regulator operatively connected to actuate said shifting means for closing the valve.
- 25 2. In a grain-weigher, the combination, with the supply-chute, the scale-beam, and the valve pivotally supported for closing said chute, of a valve-operating arm carried by the beam, a valve-actuator operated by said arm, actuator-shifting means connecting the actuator with the valve, and a regulator operatively connected to actuate said shifting means for swinging the valve.
- 30 3. In a grain-weigher, the combination, with the supply-chute and the scale-beam, and with a reducing-valve and a cut-off valve together closing said chute, of a valve-operating arm on the beam for each valve, a valve-actuator for each valve and operated by said arms respectively, actuator-shifting means connecting each valve with its actuator, and a regulator operatively connected with each said shifting means for operating the valves independently of the scale-beam movement.
- 35 4. In a grain-weigher, the combination, with the supply-chute, the scale-beam, and the swinging reducing-valve, of a valve-operating arm carried by said beam, the valve-actuator operated by said arm, and regulator-controlled actuator-shifting means connecting the actuator and valve for actuating the valve independently of the beam movement.

5. In a grain-weigher, the combination, with the swinging reducing-valve and with a scale-beam having the arm 71, of the reducing-valve actuator and regulator-controlled actuator-shifting means connecting said actuator with the reducing-valve for operating said valve independently of the movement of the scale-beam arm.

6. In a grain-weigher, the combination, with the swinging reducing-valve and with a scale-beam having the arm 71, of the reducing-valve actuator and regulator-controlled actuator-shifting links connecting said actuator and valve for operating the valve independently of the movement of the scale-beam arm.

7. In a grain-weigher, the combination, with the cut-off valve and with a scale-beam having the cut-off-valve-actuating arm, of the cut-off-valve actuator operated by said arm and regulator-controlled actuator-shifting means connecting said valve and actuator for operating the cut-off valve independently of the movement of said valve-actuating arm.

8. In a grain-weigher, the combination, with the cut-off valve and with a scale-beam having the cut-off-valve-actuating arm, of the cut-off-valve actuator operated by said arm and regulator-controlled actuator-shifting links connecting said valve and actuator for operating the cut-off valve independently of the movement of said valve-actuating arm.

9. In a grain-weigher, the combination, with the supply-chute and with a scale-beam having a valve-actuating arm, of the valve and the valve-actuator therefor, both pivotally supported on substantially coinciding axes, and regulator-controlled actuator-shifting means connecting said valve and actuator, whereby the valve and its actuator are normally maintained in a fixed relation during their axial movement derived from the scale-beam movement.

10. In a grain-weigher, the combination, with the scale-beam having the roller-provided arm, of the valve 70, the cam-provided valve-actuator operated by the roller, and regulator-controlled means connecting the valve and said actuator, whereby the valve and its actuator may be shifted relatively to each other independently of the movement of said roller.

FRANCIS H. RICHARDS.
